APPARATUS FOR THE SALE AND PURCHASE
OF ARTICLES

Howard E. Wolfe, Harrison, N. Y.

Application March 17, 1933, Serial No. 661,257

3 Claims. (Cl. 232—4)

This invention relates to methods for the sale and purchase of articles and to apparatus for retaining and releasing tokens and the like adapted for use in such methods.

5 An object of the invention is the provision of a small, inexpensive, reasonably fool-proof and safe method for the sale and purchase of articles without the meeting of the seller and the purchaser.

Another object is the provision of a token container which is simple and inexpensive of construction, inaccessible to unauthorized persons, readily operable by authorized persons, and which will efficiently serve the purposes for which it is intended.

15 Other objects of the invention will in part be obvious and will in part appear hereinafter.

The invention accordingly comprises the several steps and the relation and order of one or more of such steps with respect to each of the others, and the apparatus embodying features of construction, combinations of elements and arrangement of parts, all as exemplified in the following detailed disclosure, and the scope of the application of which will be indicated in the claims.

25 For a fuller understanding of the nature and objects of the invention reference should be had to the following detailed description taken in connection with the accompanying drawing, in which:

Figure 1 is a perspective view of a token container embodying the invention, and shows also a key by which the container may be operated;

Fig. 2 is a similar view with the front wall removed;

Fig. 3 is an enlarged detail view of a portion of a form of key and key-receiving means adapted for use in operating the container;

Fig. 4 is a longitudinal sectional view of a modified form of token container; and

Fig. 5 is an enlarged detail view of another form of key and key-receiving means which may be used in operating containers such as contemplated by the invention.

45 In the sale of articles of such character and under such conditions that the purchaser and the seller do not meet, it has always been a considerable problem to readily conduct such sales with any degree of certainty of proper payment or indeed of proper delivery. An outstanding type of such character of sales is in the delivery of bottled milk from house to house. In such sale of milk the dealer must either give credit to his customers or seek payment from them at inconvenient times, 50 which is a cause of considerable loss, annoyance,

and difficulty. In many instances, also the customer finds difficulty in assuring that the milkman will leave the varying quantities of milk, cream, etc., needed on different dates. At times notes are lost, blown away or obliterated by rain, or in some cases, ignored by the milkman, so that inadequate or excessive quantities of milk or cream are left by him.

With the foregoing and other difficulties in mind, the present invention contemplates the provision of an improved method for the dispensing of articles under the conditions in question and the provision of a token container of such construction that it is particularly adapted for such use. In this connection it is to be understood that the word "token", as utilized in connection with the apparatus in question, is used in its broad sense to include coins, as well as the usual metallic or composition tokens or other suitable pieces of material.

75 In accordance with the invention the householder or other purchaser inserts in a container tokens which are preferably of a value similar to the price of an article desired, but which may be an even fraction thereof. These are so placed in the container as to be non-releasable except by the use of a key possessed by the seller or his agent. The tokens are released by the use of the key, and a supply of articles in accordance with the number of tokens inserted is delivered 80 to the purchaser, as by leaving them on the porch of his home. If desired, a variety of tokens, each indicating different articles, may be utilized, so that the seller or his agent, upon releasing the tokens with his key, will know exactly what articles are desired without further 85 information.

90 In the drawing there is exemplified one form of a token container embodying the invention. This container comprises an enclosure 10 which is exemplified as in the form of a box. The enclosure is formed with an upper token-receiving slot and a lower discharge opening, these preferably being in the upper and lower walls of the box as exemplified at 11 and 12 respectively. 95 Interior wall members 13 and 14, in the present instance, serve to provide the side walls of a token-holding compartment, the end walls being provided by the front and rear walls of the enclosure. The bottom of the compartment is provided by a releasable member, which, in the present instance, is a slidible plate 15. From beneath the compartment the tokens, when released, are guided to the opening 12 by means of a discharge passage formed by side-wall mem- 100 105 110

bers 16 and 17. The plate is normally held across the space between the compartment and the discharge passage by means of a spring; and a stop, which may be the end wall of the container 5 of the enclosure or a continuation of the members 15 and 17 as indicated at 18, is provided to limit the movement of the plate. In order to reduce the likelihood of any tampering with the plate, there is provided a recess 19 to receive the 10 forward end thereof, and the discharge passage is preferably so formed as to have considerable length. In order to facilitate the movement of the tokens from the compartment to the discharge passage when the plate is moved from beneath tokens in the compartment, the upper 15 end of the passage is preferably formed wider than the lower end of the compartment. For instance, by disposing the upper end of the wall 17 outwardly of the lower end of the wall 14, likelihood of the tokens catching in their passage from the compartment to the discharge passage, is substantially eliminated. In the exemplified construction not only is the edge at the top of the wall 17 disposed outwardly of the edge at the 20 bottom of the wall 14, but also as a further precaution against catching, the upper edge of the wall 16 is disposed outwardly with respect to the lower edge of the wall 13. While it is desirable that the upper end of the passageway be 25 wider than the lower end of the compartment, the essential point from the standpoint of preventing tampering is that a shoulder be provided beneath the end of the plate at the side of the discharge passage.

30 In order to slide the plate from beneath tokens in the compartment, there is provided a rotary member such, for instance, as a toothed wheel, annular gear, a worm, etc., which meshes with rack means on the plate. In the present instance, the rotary member comprises a toothed wheel 35 20, the teeth of which fit into a series of openings 21 in the plate. The wheel is carried on a shaft 22 mounted in bearings 23 and 24 within the enclosure, and carries, in the present instance, a coil spring 24', tending to hold the plate against the stop 18. The front wall member 25 of the enclosure is formed with a key-receiving opening 26 and the shaft is provided with key-receiving means 27 of such nature as to prevent 40 its operation by persons not possessing the proper key, as for instance the key 28.

45 Although the exemplified mechanism is sturdy and of a type which should have a long life, it is desirable in certain instances that the box be opened with comparative ease, if necessary. To this end the exemplified enclosure is formed with a front wall 25 provided with lugs 29 arranged to fit into openings 30 in one end of the enclosure, and secured by rivets 31 at the other end. These rivets may be formed by knocking down the ends 50 of a headless screw fitting into the threaded passageways in blocks 32 in the corners of the box. To remove the front wall it is only necessary to cut off the heads of the rivets; and to replace the front wall it is only necessary to unscrew the screws and to replace them by other screws and knock down their outer ends.

55 If desired, the edge portions of the slot 11 may be raised, as indicated at 33, so as to prevent rain falling on the top of the box from running into the slot. This may be accomplished by bending over the edges of the top of the box, by soldering a wire about the slot, or in any other suitable manner.

60 70 75 The box is readily fastened to a wall, as by

means of screws 34 in screw-holes in its rear wall.

It will be understood that the construction shown may be modified in a variety of ways without departing from the broader aspects of the invention. For instance, there may be provided a construction such as shown in Fig. 4, wherein one end 35 of the box proper serves as a side-wall for the compartment and discharge passage, and also provides a recess 19a and a stop 18a for the sliding plate 15a which is pressed directly by a spring 37.

80 85 In some cases the bottom of the compartment may be provided by a plate arranged to be released by other than a sliding movement and a variety of other modifications may be made.

90 95 As will be understood, any of a wide variety of different types of keys may be utilized to operate a mechanism such as is contemplated by the invention, and the term "key" is utilized herein to describe any member separate from the mechanism which is carried by the person who is to release the tokens and which is especially constructed to operate the mechanism. One of the many other types of key and key-receiving means which may be utilized is exemplified in Fig. 5. 100 In this figure the key is shown at 38, the shaft at 22b and the key plates at 39.

105 Since certain changes in carrying out the above method and in the constructions set forth, which embody the invention may be made without departing from its scope, it is intended that all matter contained in the above description or shown in the accompanying drawing shall be interpreted as illustrated and not in a limiting sense.

110 Having described my invention, what I claim as new and desire to secure by Letters Patent is:

115 1. In a token container and releaser, means providing vertically-aligned upper and lower compartments having narrow token-passing slots in their upper and lower walls respectively, a 120 slideable plate normally separating said compartments and providing a token-retaining bottom wall for the upper compartment, means providing a recess beyond one side of said compartments for receiving one end of said plate, resilient means tending to hold said plate within said recess, the sides of said recess serving to prevent contact with the end of said plate by a tool inserted through either of said slots, and key-operated means to move said plate out of said recess and from beneath tokens in said upper compartment to permit the same to drop into the lower compartment and out of the lower slot.

125 2. In a token container and releaser, means providing vertically-aligned upper and lower compartments having narrow token-passing slots in their upper and lower walls respectively, a slideable plate normally separating said compartments and providing a token-retaining bottom wall for the upper compartment, means providing a recess beyond one side of said compartments for receiving one end of said plate, resilient means tending to hold said plate within said recess, the sides of said recess serving to prevent contact with the end of said plate by a tool inserted through either of said slots, and key-operated means to move said plate out of said recess and from beneath tokens in said upper compartment to permit the same to drop into the lower compartment and out of the lower slot, said compartments being of sufficient height with respect to their width to substantially prevent the movement of said plate by the leverage of a blade inserted through either of said slots.

3. In a token container and releaser, means providing vertically-aligned upper and lower compartments having narrow token-passing slots in their upper and lower walls respectively, a 5 slidable plate normally separating said compartments and providing a token-retaining bottom wall for the upper compartment, means providing a recess beyond one side of said compartments for receiving one end of said plate, resilient means 10 tending to hold said plate within said recess, the sides of said recess serving to prevent contact with the end of said plate by a tool inserted through either of said slots, key-operated means to move said plate out of said recess and from beneath tokens in said upper compartment to permit the same to drop into the lower compartment and out of the lower slot, and an enclosure for the said walls of said compartments and for the aforesaid means.
